Term of patent 7 years

(Cl. D57—1)

FIG. 1

FIG. 2

FIG. 3

FIG. 5

FIG. 4

FIG. 6

FIGURE 1 is a plan view of a glare shield in a flattened position showing my new design;

FIGURE 2 is a front view thereof in normal use;

FIGURE 3 is a side elevation view thereof;

FIGURE 4 is a top plan view thereof;

FIGURE 5 is a bottom plan view thereof;

FIGURE 6 is a rear elevation thereof.

The side not shown is a mirror image of the side shown.

It is to be understood that the surface ornamentation as viewed in FIGURE 1 and partially omitted in FIGURES 4 and 5 is intended to cover the entire area as indicated therein.

The headbands are omitted in FIGURE 1 and shown broken away in FIGURE 6 for convenience of illustration.

The dominant features of my design reside in the portions shown in the full lines.

I claim:

The ornamental design for a glare shield, substantially as shown and described.
